UNITED STATES PATENT OFFICE.

FRED TEASDALE, OF ROLLA, MISSOURI, ASSIGNOR OF ONE-HALF TO JOHN M. SCHUMAN, OF ROLLA, MISSOURI.

SCRAPING TOOL.

Application filed February 5, 1927. Serial No. 166,264.

This invention relates to scraping tools, and particularly, tools that are used for scraping flat surfaces formed of wood.

The main object of the invention is to provide a tool that is particularly adapted for use in scraping wood floors, due to the fact that the scraping blade can be readily detached from or combined with the blade holder, and the blade holder is of such shape and construction that the user can easily exert sufficient pressure on the blade to hold it flexed or under tension with the edge of the blade pressed tightly against the surface that is being scraped and with an intermediate portion of the blade disposed in contact with or in close proximity to a part on the blade holder that limits the flexing of the blade in one direction.

Another object is to provide a scraping tool of the character referred to, in which the blade can be easily adjusted at an angle to the blade holder when the tool is being used for scraping a surface adjacent a wall, so as to cause the portions of the holder that are engaged by the user's hands to be spaced far enough away from the wall to eliminate the possibility of the user's hands striking against the wall.

Figure 1 of the drawings is a top plan view of a wood scraping tool constructed in accordance with my invention, illustrating in broken lines how the blade of the tool can be adjusted when the tool is being used for scraping a surface adjacent a wall.

Figure 2 is a side elevational view of the tool, partly broken away, and

Figure 3 is a top plan view, illustrating the device being used for scraping a horizontal surface adjacent a wall.

Briefly described, my improved tool consists of a scraping blade A, formed preferably from a flat piece of steel, and a holder for said blade that comprises a handle B and a blade receiving portion C at one end of said handle that is bifurcated or slotted transversely at its terminal end so as to permit the inner end of the blade to be slipped into same. The slot 1 in the portion C that receives the blade extends transversely across the entire width of the terminal end of said portion and inwardly a sufficient distance from said terminal end to provide bearing surfaces for the blade that are of sufficient area to insure the blade being properly supported and maintained in

operative position without the aid of a fastening device or retaining device. The slot 1 can either correspond in width throughout its entire length to the thickness of the blade, or the extreme inner end portion of 60 said slot can be made a trifle narrower than the thickness of the blade, so as to form a shoulder 2 in said slot that serves as a stop or abutment for the inner end of the blade. While it is not necessary to use a fastening 65 device to retain the blade in operative position in the slotted portion C of the holder, said portion can be provided with a set screw or similar device 3, if desired, for clamping the blade A in the blade holder, 70 as shown in broken lines in Figure 2.

When the tool is intended primarily for use in scraping wood floors or other surfaces, which necessitate the user exerting considerable pressure on the scraping blade 75 during the scraping operation, it is preferable to arrange the terminal end of the slot 1 in the blade receiving portion C at an angle to the handle B, as shown in Figure 2, so that when the tool is in use, with the handle B grasped in the left hand of the user, and the scraping edge of the blade A in contact with the surface being scraped, the user can exert considerable downward pressure on the blade and hold it flexed slightly or 85 under tension by simply pressing downwardly on the blade receiving portion C of the holder with his right hand. The particular angle at which the slot 1 is disposed with relation to the handle B is immaterial, 90 and while I prefer to dispose the blade of the tool at an angle to the handle, so as to increase the leverage on the blade during the scraping operation, the blade A can be mounted in the blade receiving portion C 95 of the holder in such a way that it extends parallel to the longitudinal axis of the handle. Due to the fact that the blade receiving portion C of the holder is intended to be engaged by one hand of the user, in the 100 operation of scraping a surface with the tool, it is preferable to provide said portion C with a hand grip D of any preferred shape and dimensions, which is herein illustrated as consisting of a curved surface at the top side of the blade receiving portion C of the holder which is convexed both longitudinally and transversely so as to enable it to be gripped tightly by the user's hand.

In order to prevent the blade of the tool 110

from flexing too much, when the tool is in use, the blade receiving portion C of the holder is provided at its front end with a part 4 that projects forwardly from the outer end of the slot 1 in the portion C, and which overhangs the top side of the blade, the surface of said forwardly-projecting part 4 that is arranged in opposed relation to the top side of the blade being inclined 10 upwardly from the blade, as shown in Figure 2, so as to permit the blade to flex slightly and then come in contact with said part 4. Accordingly, when the tool is in use, the forwardly-projecting part 4 of the blade receiving portion C of the holder that overhangs the blade will act as an abutment or stop that limits the flexing of the blade in one direction, the abutment surface of said part being inclined relatively to the 20 blade so as to permit the blade to flex a limited degree. In the normal operation of the tool the blade A will be arranged in longitudinal alignment with the handle B, as shown in full lines in Figure 1, but when the tool is used for scraping a surface in close proximity to a wall, it is preferable to turn the blade A slightly relatively to the blade receiving portion C, as shown in broken lines in Figure 1, so that the handle B 30 and the hand grip D, which are engaged by the user's hands, will be spaced far enough away from the wall to eliminate the possibility of the user's hands striking against the wall.

35 The blade holder of the tool can be formed from any suitable material, but I have found that a blade holder constructed of hard wood is perfectly satisfactory, as it is inexpensive to manufacture and it is easy on the user's hands. The size or dimensions of the handle B and the blade receiving portion C of

the blade holder are immaterial, but I have found that when the holder is provided with a handle of approximately ten inches in length and provided with a blade receiving portion of approximately two inches in width, equipped with a slot 1 of approximately two inches in depth, that the tool is exceptionally efficient for scraping hard wood floors, due to the fact that the user 45 can easily exert the required pressure on the scraping edge of the blade and the blade of the tool can be easily removed from or inserted in the blade holder when it becomes necessary to re-sharpen the blade or replace 50 a worn blade with a sharp one.

Having thus described my invention, what I claim as new and desire to secure by Letters Patent is:

A scraping tool, consisting of a relatively 60 long handle that is adapted to be grasped by one hand of the user, a blade-receiving portion at one end of said handle, formed integral with the same and having a convexed top surface that is adapted to be engaged by the user's other hand, a slot in said blade-receiving portion disposed at an angle to said handle and extending inwardly from the terminal end of said portion, said slot 65 extending transversely across the entire 70 width of said blade-receiving portion, a laterally-adjustable blade in said slot projecting forwardly and downwardly beyond the terminal end of said blade-receiving portion, and a projection on the terminal end of 75 said blade-receiving portion that overhangs the blade and which is provided with an abutment surface for the blade that is disposed at an angle to the slot in which the blade is positioned.

FRED TEASDALE.
